UNITED STATES PATENT OFFICE.

HOWARD J. MURPHY, OF READING, MASSACHUSETTS, ASSIGNOR, BY MESNE ASSIGNMENTS, TO ALEMITE MANUFACTURING CORPORATION OF CHICAGO, ILLINOIS, A CORPORATION OF DELAWARE.

LUBRICATING APPARATUS.

Application filed January 9, 1926. Serial No. 80,247.

This invention aims to provide improvements in lubricating apparatus.

In the drawings, which illustrate a preferred embodiment of my invention:

Fig. 1 is a diagrammatic layout of a motor driven central lubricating system showing parts thereof in cross-section;

Fig. 2 is a section of one of the charge-determining lubricant devices showing the relation of the parts when the charge-determining chamber is being filled with lubricant;

Fig. 3 is a section of a charge-determining lubricant device similar to that shown in Fig. 2, but showing the relation of the parts as the lubricant is being forced from the device;

Fig. 4 is a section on the line 4—4 of Fig. 1, being partly in elevation and partly in cross-section;

Fig. 5 is a section on the line 5—5 of Fig. 1, being partly in elevation;

Fig. 6 is a plan section of the means for starting and stopping the motor; and

Fig. 7 is a sectional view of a modified form of charge-determining cup.

Referring to the drawings, I have illustrated a central lubricating system which is particularly, though not exclusively, useful for lubricating various parts of a motor vehicle.

The system shown includes a plurality of lubricant cups 1, connected by a plurality of pipes 2 to a lubricant pump 3. The piston 3^a of the pump is reciprocated by an eccentric 4 driven by a small electric motor 5. Means for starting and stopping the motor and means for reducing the pressure of the lubricant in the system after the motor has stopped are also illustrated.

The general operation of some of the parts that make up the system are substantially the same as shown and described in my co-pending application Serial No. 80,243 filed herewith. Therefore the description of this will be confined more generally to the parts of the system which are new.

The means for starting and stopping the motor 5 includes a pair of brackets 6 and 6^a secured to the dash 7 (shown in dotted lines) of the vehicle to support a shaft 8. To one end of the shaft is secured a ratchet wheel 9 which cooperates with a reciprocable pawl

member 10 mounted in one end of the bracket 6^a and reciprocated by a cam 11 driven by the motor 5. The other end of the shaft 8 supports a disk 12 of non-conducting material into which are set two circular metal pieces 13 and 14 joined together by a narrow metal piece 15 (Fig. 5). The circular piece 13 forms a complete circle and is always in contact with an electrical contact 16 carried by the bracket 6. The metal piece 14 does not form a complete circle, the ends being spaced apart to provide a break in the circuit for purposes more fully hereinafter described.

The bracket 6, which carries the contact 16, also carries a second contact 17 bearing against the disk 12 in the path of the metal piece 14, as shown in Fig. 5. The disk 12 and the contacts 16 and 17 cooperate to provide an electric switch for starting and stopping the motor. The disk is the rotary part of the switch and the contacts the stationary parts to which the wires are secured to conduct the current through the switch.

A wire 18 connects the contact 17 with one pole of the motor 5. A second wire 19 connects the contact 16 with one side of the battery 20 and a third wire 21 connects the other side of the battery with the other pole of the motor 5.

The disk 12 carries a lug 22 which projects therefrom into the path of a push rod 23 secured to the dash and normally urged away from the lug by a spring 24.

The means for reducing the pressure of the lubricant in the pipe system and in the cups comprises a small cylinder block 25 cored to provide a piston chamber 26 (Fig. 5) in which is arranged a stem 27 and a piston 28. An inlet passage 29 leads into one end of the chamber 26 while an outlet passage 30 leads out from one side of the chamber. The piston 28 may be of any suitable construction and is slidable relative to the stem. A spring 31 is interposed between the piston and an abutment 32 carried by the stem to normally press the piston against the shoulder 33 at the end of the stem as shown in Fig. 5. One end of the stem 27 extends from the block 25 and engages the outer peripheral edge of the disk 12, thereby to control the opening and closing of the outlet 30.

The charge determining device or cup which I have illustrated in Figs. 2 and 3 comprises a body portion formed of two separable parts presenting, when secured together, 5 a lubricant-measuring chamber 34, an inlet passage 35 and an outlet passage 36. Within the chamber 34 is arranged a piston 37 and valve means. The valve means includes a valve 38 at the end of a valve stem 39 secured to the piston 37, and a valve seat part 40 surrounding the stem 39. A cup washer 41 is provided to prevent leakage of lubricant around the outer periphery of the valve part 40, a metal washer 42 surrounds 10 the stem 39 and presses against the washer 41 and a spring 43 is interposed between the piston 37 and the washer 42 normally to keep the valve 38 against its seat as illustrated in Fig. 2. The chamber 34 is enlarged slightly at the inlet end and a relatively weak spring 44 is interposed between the wall at the outlet end of the chamber 34 and the valve seat part 40 normally to urge 15 the valve means and piston as a unit toward the inlet end of the chamber.

Assuming that the parts of the system are in their normal positions, as indicated in Fig. 1, the various parts of the vehicle (not shown) which are to be lubricated by 20 the central lubricating system may be efficiently and quickly lubricated and the operator need merely push on the push rod 23 to do so. As the push rod 23 engages the lug 22, the disk 12 is turned slightly so 25 as to bring the energized part 14 into contact with the contact 17, thereby completing a circuit from the battery 20 to start the electric motor 5. The motor rotates the shaft 5^a to which the cams 11 and 4 are secured. The cam 4 in turn operates the 30 plunger 3^a of the pump 3 to draw lubricant from the lubricant reservoir 45, which may be the crankcase of the vehicle, and forces it through the pipe system 2 to the cups 1, as more fully described in the above-mentioned application.

The lubricant enters the inlet passage 35 of the lubricant cup 1 and flows around the piston into the chamber 34 because of the 35 enlargement at the inlet end thereof. As the valve 38 is normally closed (Fig. 2) the lubricant is trapped in the chamber 34 until it becomes filled. Then the lubricant acts upon the piston and valve means and forces the whole as a unit against the pressure of the spring 44 to close the space around the piston 37. Immediately after the supply of lubricant to the chamber 34 is cut off by the piston 37, the spring 44 becomes fully 40 compressed and provides a stop against further movement of the valve seat part 40, cup washer 41 and washer 42. As the piston 37 continues on its way into the chamber 34, it unseats the valve 38. As the diameter of 45 the stem 39 is smaller than the hole through

the valve part, the lubricant may be forced from the chamber through the outlet passage 36 to the part to be lubricated.

An important feature of the cup is the arrangement of parts together with the use 70 of a cup washer as part of the piston 37 to permit absolutely cutting off the passage of lubricant around the piston to the chamber 34 prior to opening the valve 38, thereby insuring the forcing of a measured quantity 75 of lubricant from the cup at each operation. The cup leather of the piston permits passage of lubricant from the chamber 34 to the inlet side of the piston 37 during the movement of the piston from the time it cuts off the supply of lubricant to the chamber until the valve opens. Thereafter the lubricant presses the cup washer against the wall of the chamber 34 and prevents further leakage so that all the lubricant may be 80 forced out of the chamber.

During the time that the lubricant measuring and expelling means in each cup is operating as described, the cam 11 operates the reciprocable pawl member 10 to turn the 90 ratchet wheel 9. The wheel 9 rotates the shaft 8 and, as the disk 12 is carried by the shaft, it in turn is rotated relative to the contacts 16 and 17. This operation continues until sufficient lubricant has been forced from 95 the pump 3 to the cups 1 to force the required amount of lubricant from each cup. The amount of lubricant required may be determined by the number of strokes of the piston 3^a required to supply the required 100 volume of lubricant for all of the cups, depending upon the size of the chamber in the pump 3. For each stroke of the piston 3^a the ratchet wheel 9 is turned one tooth so that the number of teeth equals the 105 number of strokes required of the piston plus the number of teeth it takes to fill the space which the wheel is turned when the push rod 23 is operated. When the pump 3 has forced the required quantity of lubricant to 110 the cups 1, the disk will be turned to the position shown in Fig. 5 with the contact 17 out of engagement with the metal piece 14, thereby breaking the circuit and stopping the 115 motor 5.

During the operation of forcing lubricant to the cups, the piston 28 in the cylinder 25 (Fig. 5) is held at the forward end of the chamber 26 adjacent to the inlet passage 29 by the spring 31 and also by the disk 12 120 which presses the stem 27 inwardly, thereby preventing passage of lubricant through the passage 30. As the disk turns, it keeps the stem 27 pressed inwardly until it has been turned to allow the stem to enter a low spot 125 or detent 45. This detent 45 is located at a point on the edge of the disk which will be opposite the end of the stem 27 when the contact 17 runs off the end of the piece 14 as above described. Thus as the motor stops, 130

the lubricant moves the piston 28 with the stem 27 to uncover the outlet passage 30 (Fig. 5) so that the lubricant may pass out of the pipe system 2 through the pipe 46, through the chamber 26 and then through the pipe 47 back into the crank case above the level of the lubricant therein to relieve the pressure as shown in Fig. 1.

The piston 28 is made slidable on the stem 27 to provide safety valve means which will operate to relieve the pressure at any time regardless of the relative position between the stem and the disk. That is to say, if for any reason the lubricant in the system reaches a pressure which is greater than is required to press all of the pistons in the cups to the ends of the chambers in the cups, then the spring 31 will yield and allow the piston to pass the passage 36 and relieve the system of its excess pressure.

As the motor 5 stops, the various parts of the system automatically assume their normal positions so that they may be ready for immediate operation when the motor 5 is again set in motion.

Fig. 7 illustrates a second form of lubricant measuring device or cup for use with the system shown and described. While this cup is constructed in a slightly different manner, its operation is substantially the same as shown and described in connection with the cup shown in Figs. 2 and 3.

The cup shown in Fig. 7 includes a measuring chamber 48, inlet and outlet passages 49 and 50, a piston 51 and a valve 52 substantially as shown in Figs. 2 and 3. In this instance, however, the valve seat 53 is formed integral with the body of the cup between the chamber 48 and the outlet passage 50. Instead of the piston and valve stem being secured together as in Figs. 2 and 3, the piston 51 is here shown as slideable relative to the valve stem 54, and stops 55 and 56 are carried by the stem 54 to limit the movement of the piston relative to the stem. A spring 57 is interposed between the piston 51 and the wall at the end of the chamber 48 normally to urge the piston into the enlarged portion of the chamber, and a second spring 58 is placed in the outlet passage 50 to press the valve 52 against its seat 53.

In operation the lubricant first fills the chamber 48, then moves the piston relative to the stem 54 to cut off further passage of lubricant into the chamber 48, then upon continued movement of the piston it engages the stop 55 and thereafter moves the valve stem 54 to open the valve 52 against the pressure of the spring 58 to permit the lubricant to flow from the chamber 48 through the passage 50 to the part to be lubricated.

While I have shown and described a preferred embodiment of my invention, it will be understood that changes involving omis-

sion, substitution, alteration and reversal of parts and even changes in the mode of operation may be made without departing from the scope of my invention, which is best defined in the following claims.

The oil cup for measuring valve per se, disclosed herein, is claimed in my copending divisional application, Serial No. 333,926, filed January 17, 1929.

Claims:

1. A central lubricating system including a plurality of charge measuring and charge delivering lubricant cups, a power-driven piston pump connected to said cups by a pipe system, means for starting the operation of said pump to force a definitely measured quantity of lubricant through the pipe system to said cups and means associated with said pump for stopping the operation of said pump after the piston in said pump has operated a predetermined number of strokes sufficient to charge said cups.

2. A central lubricating system including a plurality of charge measuring and charge delivering lubricant cups, a pump having a piston therein for forcing lubricant through a pipe system to said cups, piston operating means and means for stopping the operation of said piston operating means upon completion of a given number of strokes of said piston, whereby a measured quantity of lubricant will be forced to said cups.

3. A central lubricating system including a plurality of charge measuring and charge delivering lubricant cups, a pump having a piston therein for forcing lubricant through a pipe system to said cups, piston operating means and mechanically operated means driven by said piston operating means for automatically stopping the operation of the piston immediately subsequent to the completion of a predetermined number of strokes of the piston, whereby a measured quantity of lubricant sufficient completely to charge said cups will be forced into said pipe system and delivered to said cups.

4. A central lubricating system including a plurality of charge measuring and charge delivering lubricant cups, a pump having a piston therein for forcing lubricant through a pipe system to said cups, electrically driven means for reciprocating the piston in said pump, and electric circuit breaking means cooperating with said electrically driven means to stop the operation of said pump after a predetermined number of strokes of the piston, whereby a measured quantity of lubricant sufficient to fill all of said cups will be forced into said pipe system.

5. A central lubricating system including a plurality of charge measuring and charge delivering lubricant cups, a pump having a piston therein for forcing lubricant through a pipe system to said cups, an electric

motor for driving means for reciprocating said piston, a switch for making and breaking a circuit to start and stop said motor, ratchet and pawl means connected with 5 said switch and operated by means driven by said motor to turn one of the contacts of said switch relative to the other to stop said motor when a predetermined quantity 10 of lubricant has been forced from said pump.

6. A central lubricating system including a plurality of charge measuring and charge delivering lubricant cups, a pump having a piston therein for forcing lubricant through a pipe system to said cups, an electric motor for driving means for reciprocating said piston, a switch for making and breaking a circuit to start and stop said motor, manually operable means for operating 15 said switch to complete a circuit for starting said motor, ratchet and pawl means operated by said motor for breaking the circuit to stop said motor after a predetermined quantity 20 of lubricant has been forced to said cups by said pump.

7. In a central lubricating system of the class described, an electric motor driven pump, a control switch therefor having a rotary part carrying one of the contacts of 30 the switch, a stationary contact for cooperation therewith and a lubricant pressure reducing device cooperating with the rotary part of said switch so as to relieve the lubricant pressure in the system when said 35 rotary part reaches a predetermined point during its rotation.

8. In a central lubricating system having a pump driven by a motor, an electric switch for starting and stopping said motor, said 40 switch comprising an intermittently driven disk having an energized portion adapted to turn therewith, a stationary contact normally out of contact with said energized portion of said disk, a lug projecting from 45 said disk, a hand-operated plunger for en-

gagement with said lug to move said disk so as to bring said energized portion into contact with said stationary contact for starting the motor for operating said pump, intermittently operating means operated by 50 said motor to continue the rotation of said disk until the energized portion is moved out of contact with said stationary contact and a lubricant pressed plunger located in a cylinder block adjacent said switch and 55 having a stem bearing against said disk to prevent said piston opening a port in said cylinder block until said stem enters a detent in said disk thereby relieving the pressure in the system. 60

9. In a central lubricating system having a pump driven by a motor, an electric switch for starting and stopping said motor, said switch comprising an intermittently driven disk having an energized portion adapted 65 to turn therewith, a stationary contact normally out of contact with said energized portion of said disk, a lug projecting from said disk, a hand-operated plunger for engagement with said lug to move said disk 70 so as to bring said energized portion into contact with said stationary contact for starting the motor for operating said pump, intermittently operating means operated by 75 said motor to continue the rotation of said disk until the energized portion is moved out of contact with said stationary contact and a lubricant pressed plunger located in a cylinder block adjacent said switch and having a stem bearing against said disk to prevent said piston opening a port in said cylinder block until said stem enters a detent in said disk thereby relieving the pressure in the system, said piston movable against the pressure of a spring to relieve 80 the system of excess pressure even prior to the entrance of said stem into said detent.

In testimony whereof I have signed my name to this specification.

HOWARD J. MURPHY.
